UNITED STATES PATENT OFFICE.

JACOB S. HOVLAND, OF CHICAGO, ILLINOIS.

GLAZIER'S HAMMER.

SPECIFICATION forming part of Letters Patent No. 752,454, dated February 16, 1904.

Application filed September 11, 1903. Serial No. 172,741. (No model.)

To all whom it may concern:

Be it known that I, JACOB S. HOVLAND, of Chicago, in the county of Cook and State of Illinois, have invented certain new and useful 5 Improvements in Glaziers' Hammers; and I do hereby declare that the following is a full, clear, and exact description thereof, reference being had to the accompanying drawings, and to the letters of reference marked thereon, which form a part of this specification.

This invention relates to implements for glaziers' use.

One object is to produce a hammer which shall be so shaped and proportioned as to be 15 a relatively light implement and at the same time sufficiently heavy to be effective for its intended use in driving flat brads, pins, or diamonds into the wooden sash of a window-frame.

Another object of the invention is to produce a hammer having such shape that the user may take hold of it in any manner at the handle and find it ready for use on the instant—that is to say, either end of the head 25 may be used as the driving end with either face of the hammer uppermost.

Another object of the invention is to produce a hammer which shall be neat in appearance, durable in use, relatively cheap, and 30 which may also be used to cut or scrape putty or other similar objects.

These and other advantages of my invention will be fully recognized in view of the attached drawings and accompanying description and claims.

In said drawings, Figure 1 illustrates in a perspective view a glazier's hammer constructed in accordance with my invention. Fig. 2 is a side view of the head. Fig. 3 is an end 40 view of the head. Fig. 4 is a side view of a modified form of head, and Fig. 5 is an end view of still another modification of the construction of the head.

Referring now more particularly to Figs. 1, 45 2, and 3, the letter A designates the hammer as a whole, a being the head and b the handle, of wood or other suitable material. This handle may be of any suitable shape; but I have found that the most convenient handle is one 50 which embraces the grip portion proper, b,

having a shouldered tenon or end b', (shown in dotted lines in said figures,) adapted to engage with a wedge fit a suitable recess in the shank a' of the head a. As shown in said Figs. 1, 2, and 3, the head is of symmetrical 55 configuration, its shank a' being disposed centrally of both median lines, as clearly seen in Figs. 2 and 3. The ends a² of the head in this the preferred form are extended equally on either side of the shank a'. The shank a is 60 truncated in form, being largest where it unites with the hammer proper.

The hammer-head a is in the form of an isosceles triangle in cross-section, (see end view, Fig. 3,) its two sides a³ a³ being equal, 65 and is united to the shank a' at the base of the triangle. The end faces a⁴ are flat and constitute the hammer-faces proper. The apex of the triangle forms a relatively sharp straight edge a⁵ sufficient for many uses to which a 70 putty-knife is employed, although it is not designed for or as a putty-knife. The edge a⁵ is parallel with the base of the triangle. The sides a³ a³ are straight and smooth and in a plane at right angles with the plane of the end 75 faces a⁴ a⁴.

In the modification outlined in Fig. 4 one end a² is omitted, the faces a⁴ a⁴ and the balance of the tool being precisely as heretofore described; but the plane of one face a⁴ is coincident with one side or face of the shank a', as clearly illustrated.

In the other modified form, as shown in Fig. 5, the head in cross-section is that of a right-angled triangle, one of the faces, a³, being in a 80 plane coincident with the side of shank a'.

While some of the advantages of my invention may be attained by the use of these and other modifications, I prefer the construction shown in Figs. 1, 2, and 3 and first described 90 as being neat, simple, durable, and exceedingly effective. With this preferred form the glazier need pay no attention to the position of the tool as he picks it up, since when either face a³ rests upon the sheet of glass either end 95 face a⁴ will be in the desired position for driving the pin or diamond. One of the objects of extending the ends a² is to give a desired weight to the implement for use as a hammer, and by having two of such ends, as in the 100

2 preferred form, the tool is more evenly balanced.

Having now described my invention, what I claim, and desire to secure by Letters Patent, 5 is as follows:

1. A glazier's hammer, the driving-head of which has driving-faces at its ends and outwardly-converging flat, side bearing-faces which extend the entire length of the head, 10 said faces being adapted to rest in contact with a flat surface when the handle of the hammer is held at an angle to said surface.
2. A glazier's hammer comprising a handle or grip, and a head provided with a socketed 15 shank to receive the handle end, said head having driving-faces at its ends and outwardly-converging, flat, side bearing-faces which extend the entire length of the head.

3. A glazier's hammer, comprising a handle proper and a head, the latter having a socketed shank for engagement with the handle end, two equally-beveled bearing-faces, as $\alpha^3 \alpha^3$, and two equally-extending driving ends, as $\alpha^2 \alpha^2$, each of the latter being provided with a suitable driving-face, as α^4 , the bearing-faces 25 forming an edge α^5 , substantially as shown and described.

In testimony that I claim the foregoing as my invention I affix my signature, in presence of two witnesses, this 15th day of August, 30 A. D. 1903.

JACOB S. HOVLAND.
